RAILWAY CAR END ARRANGEMENT

Walter B. Dean, Narberth, and Raymond J. Theriault, Glenside, Pa., assignors to The Budd Company, Philadelphia, Pa., a corporation of Pennsylvania

Application October 2, 1945, Serial No. 619,826

7 Claims. (Cl. 105—10)

1

The invention relates to railway cars, and particularly to the end construction of such cars as provide a central passageway between coupled cars.

The cars to which the invention relates are usually equipped with a combined buffer and face plate having a flat face surrounding a doorway opening therein and engaging, when two such cars are in coupled relation, a corresponding face plate of the adjoining coupled car. The face plates of the adjoining coupled cars are normally yieldingly urged outwardly to engage each other through their flat faces with considerable force, particularly in their lower regions, and they are preferably supported for limited yieldingly restrained universal movement with respect to the adjacent car body ends.

When the car couplers are in tension, i. e. subject to draft forces, the resilient draft gear usually provided allows the coupled car ends to separate slightly, but such separation is not sufficient to allow the face plates, urged outwardly by resilient means under considerable compression when the cars are coupled, to separate from each other. When the couplers are in heavy compression as happens under heavy forces in buff, the face plates are forced together with increased pressure and there results therefore a strong frictional resistance to relative lateral or vertical movement of the two face plates under such pressure engagement.

It is desirable to have the face plates of adjoining coupled cars move together under small relative vertical or lateral movements of the coupled car body ends, in order to avoid the grating noise and wear produced by the sliding of the flat faces of the plates on each other. Such relative movements of the car body ends occur wherever there are slight irregularities in the tracks even on straightaway tracks and on curves, dips or rises in the track. To effect such movement together, the face plates are so yieldingly mounted on the car body ends that they have limited resiliently restrained movement, both laterally and vertically, as well as the usual in and out and angular movement, the latter in particular taking place when the coupled cars are rounding a curve in the track.

To allow excessive such movement of the face plates is not desirable because, among other things, it unnecessarily complicates the mounting of the face plates and increases the overall weight of the cars. Since the tendency to excessive such movement between car body ends is however encountered under certain conditions of operation,

2

it is desirable to prevent such excessive movement between the face plates by providing a solid engagement between the face plates and their respective car body ends, and thereby prevent such excessive movement and possible damage of the means normally holding the face plates yielding outwardly from their respective car ends. In other words, the support for the face plates from the car ends yieldingly restrains vertical or lateral movement of the face plates with respect to the adjacent cars up to a certain slight degree of such movement to avoid grating noises and wear in such slight degrees of movement, but if excessive movement tends to occur, then the face plates are solidly engaged with their adjacent car ends to prevent such excessive relative movement.

It is an object of the invention to provide a car end construction of this class which allows the desirable limited universal movement of the face plate opposed by yielding restraining means, but which provides a positive stop to prevent such excessive movement as might result in injuring the parts yieldingly restraining the face plate.

It is a further object of the invention to provide for such yieldingly restrained vertical and lateral and angular movement of the face plate, but in which there is provided simple means for normally yieldingly holding the face plate central or for returning it to central position when displaced therefrom.

Other and further objects and advantages and the manner in which they are attained will become apparent from the following detailed description when read in connection with the drawings forming a part hereof.

In the drawings:

Fig. 1 is an end elevational view of a railway car equipped with the invention.

Fig. 2 is an enlarged fragmentary horizontal sectional view, taken substantially along the line 2—2 of Fig. 1, through the adjacent ends of two coupled cars showing the relative positions of the parts under normal straightaway operating conditions, one car being shown with a vestibule and side doorway and the other without.

Fig. 3 is a sectional view similar to Fig. 2, the section in this case being taken substantially along a plane indicated by the line 3—3 of Fig. 1, the parts being shown in the relative positions which they normally occupy in rounding a curve in the track.

Figs. 4 and 5 are fragmentary vertical sectional views taken, respectively, substantially along the lines 4—4 and 5—5 of Fig. 2.

Fig. 6 is a detail sectional view taken substantially along the line 6—6 of Figs. 2 and 3.

Fig. 7 is a fragmentary side elevational view on a reduced scale showing the support of the diaphragm face plate from the car end wall, parts being broken away and shown in section.

In the drawings the invention is shown applied to a railway car having a side wall and underframe construction generally similar to that disclosed in copending applications Serial No. 585,899, filed March 31, 1945, now Patent No. 2,504,659 issued April 18, 1950, and Serial No. 588,866, filed April 17, 1945, now Patent No. 2,504,113 issued April 18, 1950, respectively, but the specific side wall and underframe construction has no necessary relation to the invention except as modified to incorporate the features of the invention, and it will be understood that the showing is merely illustrative of one form of car body construction to which the invention may be applied.

The car body may comprise the end wall 10, connected at sides and top to the side walls 11 and the roof and at the bottom to the car body underframe 12. The transverse end member of the underframe may comprise a sill casting 13 rigidly secured to a center sill structure 14 as by horizontal weld lines, indicated at 15, Fig. 3, and vertical weld lines indicated at 16, Fig. 3. The center sill has spaced vertical side walls 17, 17 welded at 16, to the vertical webs 18, 18, of the end sill casting 13. It has upper and lower horizontal bracing webs 19 and 20 which are secured to the end sill casting by horizontal weld lines, as 15.

Between the side walls 17, 17 is disposed a usual form of yielding buffer 21 acted on by the central buffer stem 22 guided in the end sill casting and projecting beyond its outer face 23. On opposite sides of the buffer stem are arranged a pair of hollow projections or bosses, 24, 24, generally annular in cross section but of less vertical than lateral dimension, and tapering toward their outer ends, the projections also extending beyond the outer face 23 of the end sill casting for a purpose to be hereinafter described.

These projections are disposed in longitudinal alignment with the vertical webs 18, 18 which are bifurcated at their ends to brace the bases of the projections. Laterally of the bosses or projections 24, the casting is formed with longitudinal openings 25, 25 which loosely receive the side stems 26, 26 therethrough.

The center stem is urged outwardly by the usual buffer spring (not shown) and has abutting engagement with the transverse buffer casting 27 forming the lower transverse member of the face plate assembly, generally designated 28. The side stems 26, 26 are hinged at their outer ends at 29, 29, to the buffer casting 27 and at their inner ends they extend loosely through brackets 30, 30 secured to the respective side walls 17, 17 and upper bracing webs 19, 19 of the center sill. They are constantly urged outwardly by the coil springs 31, 31 reacting against shoulders 32, 32, and the respective brackets 30, 30.

The side stems, as clearly appears, in Fig. 3, have substantial clearance between them and the respective openings 25 in the end sill casting, to permit limited movement both vertically and horizontally between their outer ends and the end sill casting. To facilitate this swinging movement of the side stems, the brackets 30, 30 are provided with re-entrant ball faced seats 36,

36 for cooperation with similar bosses on washers 33, 33, interposed between the springs 31, 31 and the respective brackets 30, 30.

Outward movement of the side stems is limited by nuts 34, 34 screwed onto their inner ends and washers 35, 35 having bosses similar to the washers 33, 33 and adapted to engage re-entrant seats similar to seats 36, 36 on the opposite sides of the brackets 30 from the re-entrant seats engaged by washers 33, 33.

According to the invention, simple leaf spring means are provided for normally holding the buffer and face plate assembly central. Such means may comprise the double multi-leaf cantilever springs 37, 37, one interposed between each side stem and the adjacent vertical side wall 17 of the center sill. The inner end of each spring 37 is loosely held by a bracket, as 38, secured to the upper center sill bracing web 19, while its outer end bears against the bearing plate, as 39, secured to the inboard side of the adjacent side stem 26, the central clamping sleeve 40 of the spring being seated in a socket 41 secured to the adjacent side wall 17 of the center sill.

The weight of the buffer and face plate assembly 28 may be carried by the end wall of the car 10, which includes the spaced collision posts 42, 42, in a manner similar to that shown in Patent No. 2,415,385, issued February 4, 1947 to W. B. Dean et al., and entitled "Diaphragm Support for Railway Cars." This support is through the hanger rods, 43, 43 (see Figs. 1 and 7) pivoted at their lower ends at 44, 44 (see Figs. 2 and 7) to the respective sides of the face plate assembly and at their upper ends having cushioned connections 45, 45, with brackets 46, 46 secured to the respective collision posts. The pivotal connection at their lower ends is a loose connection, and the cushioned connection at the top is through rubber cushions so as to permit slight up and down and sidewise movement of the face plate assembly 28.

At the top, the face plate assembly 28 is held yieldingly spaced from the end wall 10 by a usual transverse leaf spring 47, the central portion of the spring being connected to the face plate assembly 28 and the ends having a usual pivotal connection at 48, 48, to the car end wall, see Fig. 1.

The face plate assembly 28 is shown as comprising a face plate proper extending around the sides and top of a doorway opening and forming with the buffer casting facing plate 50, a flat face for engagement with a corresponding face plate on an adjoining coupled car. This face plate is connected at sides and top to the end wall by a usual flexible inner diaphragm 51. As shown, the face plate assembly also supports spring pressed hinged side members 52, 52 which are connected by an outer flexible diaphragm 53 to the outer margin of the sides and top of the car to form a streamline continuation thereof.

It will be understood that the invention is not limited to this particular type of face plate assembly, but is equally applicable to other forms of face plate assemblies, having no outer diaphragm support.

According to the invention, the buffer casting 27 is provided opposite the projecting bosses 24 with recesses 54 of somewhat larger dimensions both vertically and laterally than the outer dimensions of the bosses, these recesses being designed to cooperate with the bosses under certain condition to provide positive stops which prevent

excessive lateral and/or vertical relative movement between the face plate assembly and the car end.

To facilitate the assembly or dis-assembly of the side stems 26 without removing the face plate assembly 23, the brackets 30 are preferably longitudinally split in planes passing through the respective openings therein, into two parts, normally held together by bolts 55. When it is desired to remove a side stem the hinge bolt 29 connecting the stem to the buffer casting, and the bolts 55 connecting the two part bracket are removed, after which the bracket parts can be separated, as shown in dotted lines in Fig. 6 and the side stem and spring assembly can be inwardly withdrawn, the openings 25 in the end sill casting being sufficiently large to permit the outer enlarged end of the stems to pass through them. It can be similarly readily assembled in the reverse order.

With the face plate mounting herein described, it will be seen that it is mounted for universal movement to a limited extent in all directions, but is restrained against such movement by yielding means. Such movement is desirable to allow the two face plates of adjoining coupled cars to follow each other's movements to a limited extent, such as occurs when the cars are moving along a fairly smooth track, without sliding on each other and thereby producing grating noises. Normally the face plates are held central by the leaf springs 37, 37, as shown in Fig. 2. The lost motion extension of the side stems through the openings 25 in the end sill permits limited lateral movement of the face plates with respect to the end sill against the pressure of said springs. If the face plates are forced laterally when the cars are in buff the frictional engagement between them is sufficiently great to overcome the centering springs 37 and may cause bending of the side stems, if they are moved laterally an excessive amount, by engagement with the sides of the openings 25. Under such conditions, the bosses 24 extending between the sides of the recesses 54 positively prevent such excessive lateral movement, by striking the adjacent sides of the recesses before the side stems engage the sides of the openings 25.

The same positive limitation of the vertical movements of the face plate is prevented by the bosses 24 striking the top or bottom walls of the recesses 54 before the side stems strike the tops and bottoms of the openings 25.

This arrangement permits the use of lighter side stems without exposing them to the danger of injury on excessive lateral or vertical movements of the face plate, which may occur under excessive buff forces especially while rounding a curve or in going over a hump or depression in the tracks.

Fig. 3 shows how one of the projections 24 enters a depression or recess 54 in rounding a curve even when the cars are in normal coupled relation without excessive buff, and since the tendency to excessive lateral movement of the face plates is accentuated, due to centrifugal force, in rounding a curve, this insures that such excessive movement cannot occur under these conditions under any conditions of operation.

The center stem 22 engages the buffer casting 27 through its rounded end by a simple abutting engagement and does not interfere to any material extent with the desired limited lateral and vertical movements of the face plate. The center and side stems together resiliently maintain

the buffers and face plates proper of two coupled cars in engagement under all conditions of operation.

While a specific embodiment of the invention has been herein described in detail it will be understood that changes and modifications may be made by those skilled in the art without departing from the main features of the invention and such changes and modifications are intended to be covered in the appended claims.

We claim:

1. A railway car end arrangement comprising a car body end framing, a diaphragm face plate assembly, including a bottom transverse member, supported from said end framing, yielding means associated with said support permitting limited universal movement including lateral and vertical movement of said face plate assembly with respect to the car body end framing and cushioning such movement, and positive stop means comprising a direct metal to metal engagement between the bottom transverse member of said face plate assembly and the car body end framing for positively limiting the cushioned relative lateral and vertical movements of said face plate assembly.

2. A railway car end arrangement comprising a car end frame including a transversely extending end underframe member, a center sill structure secured to said end underframe member, a buffer carrying a face plate supported in outwardly spaced relation from said end underframe, means for yieldingly urging the buffer and face plate outwardly including side stems having their outer ends pivoted to said buffer and passing through openings freely receiving them in the end underframe member and, adjacent their inner ends, passing through guiding means secured to the center sill structure, said side stems flanking the opposite sides of the center sill structure in spaced relation thereto, and resilient means operatively engaging the respective stems near their outer ends and removably interposed between the opposite sides of said center sill structure and the respective side stems to yieldingly hold said buffer and face plate centered but permitting cushioned lateral movement thereof.

3. A railway car end arrangement comprising a car end frame including a transversely extending end underframe member, a diaphragm face plate assembly supported in outwardly spaced relation from said end frame, means for yieldingly urging the face plate assembly outwardly including side stems passing through openings freely receiving them in said member, yielding means engaging said side stems laterally for holding said face plate assembly centered but permitting limited cushioned lateral movement thereof, and positive stop means directly between said face plate assembly and said transverse member for stopping said lateral movement before either side stem forcibly engages the side of its associated opening.

4. A railway car end arrangement comprising a car end frame including a transversely extending end underframe member, a center sill structure secured to said end underframe member, a diaphragm face plate assembly supported in outwardly spaced relation from said end frame, means for yieldingly urging the face plate assembly outwardly including side stems mounted in said transverse member for limited lateral movement with respect thereto and extending inwardly thereof in flanking but spaced relation

to the opposite sides of said center sill structure, their inner ends being guided by brackets secured to the center sill structure, and a pair of readily mountable and demountable leaf spring elements, one interposed between each side stem and the adjacent side of said center sill structure and engaging the associated side stem near its outer end, for normally holding the face plate assembly centered but permitting cushioned limited lateral movements thereof.

5. A railway car end arrangement comprising a car body end framing, a diaphragm face plate assembly, including a bottom transverse member, supported therefrom from said end framing, yielding means associated with said support permitting limited lateral movement of said face plate assembly with respect to the car body framing and cushioning such movement, and positive stop means comprising a direct metal to metal engagement between the bottom transverse member of said face plate assembly and the car body framing for limiting the cushioned relative lateral movements of said face plate assembly.

6. A railway car end arrangement comprising a car body underframe including a transversely extending end member, a buffer member supported outwardly of said end member, and yielding means for urging said buffer member outwardly, said means including side stems pivoted to the buffer member and passing freely through openings in said transversely extending member, an inner abutment means surrounding and loosely guiding the inner ends of said stems, springs interposed between said stems and the 30 35 abutment means, said abutment means being

split lengthwise of the associated stem into two separable parts, to permit ready assembly of the side stems and springs with, and disassembly from, the underframe and buffer without removing the buffer from its normal position.

7. A railway car end arrangement comprising a car body end framing including a transversely extending end member, a buffer member supported outwardly from said end framing for in and out angular and limited transverse movement with respect thereto, means yieldingly restraining the movements of said buffer member, and positive stop means between said buffer member and said end member for positively limiting the yieldingly restrained lateral movements of the buffer member, said means comprising integral projections on one of said members adapted to project into recesses loosely receiving them on the other.
